[57]**CLAIM**

The ornamental design for a band design for footwear, as shown and described.

DESCRIPTION

FIG. 1 is a right side view of a band design for footwear according to the present invention;

FIG. 2 is a left side view thereof;

FIG. 3 is a front view thereof;

FIG. 4 is a rear view thereof;

FIG. 5 is a bottom view thereof; and,

FIG. 6 is a perspective view thereof.

The broken line showing of the footwear upper is for illustrative purposes only and forms no part of the claimed design.
